J. HOLTZMAN

RAZOR BLADE HOLDER

Filed July 31, 1924

Patented Nov. 1, 1927.

1,647,357

UNITED STATES PATENT OFFICE.

JOHN HOLTZMAN, OF NEW YORK, N. Y.

RAZOR-BLADE HOLDER.

Application filed July 31, 1924. Serial No. 729,283.

This invention relates to a razor blade holder.

The object of the razor blade holder is to be enabled to strop, hone or otherwise sharpen both sides of each of the cutting edges of a double edge razor blade, without injury to the strops or other means employed to sharpen the razor blade and without injury to the razor blade when located in different positions to sharpen its opposite cutting edges.

In the accompanying drawings Fig. 1 represents a side elevation of an exemplification of my improved razor blade holder with its elements in an open or spaced position; Fig. 15 2 shows an elevation similar to Fig. 1 with a pair of its elements in a closed position; Fig. 3 indicates a side elevation of the razor blade holder with all of its elements in one of their closed positions; Fig. 4 is a section of Fig. 2 on the line 4, 4 and Fig. 5 represents a section of Fig. 2 on the line 5, 5.

Referring to Figs. 1 to 5 inclusive, the razor blade holder is indicated with the tubular handle 20, which has formed therewith the side plates 21 having the central extensions 22.

A holder member with the body portion 25 has one end thereof located between the extensions 22 and is hinged thereto, by means of the hinge pivot 26. The said holder blade 25 has extending therefrom the guard comprising the branch guard arms 27, integral therewith which join with the main guard arm 28 that is parallel to the body portion 25 and integral with the said branch guard arms. The end of the holder member 25 is formed with the curved depression 29 and has formed therein the openings 30. The said branch guard arms 27, guard arm 28 and holder member 25 are integral with each other.

A second holder member with the body portion 35 has one end thereof located between the extensions 22, and is also hinged thereto, by means of said hinge pivot 26. The holder member 35 has extending therefrom the guard comprising the branch guard arms 37 integral therewith, which join with the main guard arm 38 that is parallel to the body portion 35 and integral with the branch guard arms 37. The end of the body portion 35 has formed therewith the curved depression 39 which normally bears against the curved depression 29. Locking ears 40 extend from the body portion 35 over the openings 41 therein.

The said branch guard arms 37, guard arm 38 and holder member 35 are integral with each other.

A razor blade 45 is indicated with the opposite cutting edges 46 and 47 and the circular opening 48.

When the razor blade 45 is to be honed or sharpened it is connected to the razor blade holder, by first locating the holder members 25 and 35 in their open or spaced relation as indicated in Fig. 1. The razor blade 45 is then located upon the body portion 35, with the locking ears 40 extended through a pair of the openings 48 of the said razor blade. 70 The holder member with the body portion 25 is then swung over the razor blade 45, and the openings 30 are locked with the locking ears 40, as indicated in Fig. 2, with the depression 39 bearing against the depression 29. Both the body portions 25 and 35 with the razor blade 45 locked between them, are then swung to the position indicated in Fig. 3, in which location the cutting edge 47 of the razor blade can be honed or sharpened. 80 If it is desired to hone or sharpen the cutting edge 46 of the razor blade 45, both holder blades 25 and 35 are swung one hundred and eighty degrees, and locked with the other end of the side plates 21 of the handle 20.

To disengage the razor blade 45 from the holder member they are again swung to the position indicated in Fig. 2 when the holder blade with the body portion 25 is unlocked from the holder member having 90 the body portion 35 as indicated in Fig. 1, and the razor blade 45 can then be easily detached by disengaging its openings 48 from the locking ears 41.

It will be noted that the razor with holder can be used with the ordinary razor strop as used by barbers or with other means to engage the cutting edges of the razor blade.

When the razor blade holder is used the branch guard arms 27 and 37 on account of their flexibility will yield and permit the cutting edges 46 and 47 which are next to the strop or other honing instrumentality to bear thereon, below the guard arms 28 and 38. The latter also protect the cutting edges of the razor blade 45 when it is swung to its different positions to lock the holders 25 and 35 with the side plates 21 of the holder 105 20. The guard arms 28 and 38 prevent the razor blade cutting the strop during the stropping of the blade or injuring any other sharpening means.

It will be noted that the said holder member having the body portion 25 with its main guard arm 28 and branch guard arms 27, and the holder member having the body portion 35 with its main guard arm 38 and its branch guard arms 37, constitute both a supporting and safety device for the razor blade 45, preventing injury to either cutting edge of said blade.

10 Various modifications may be made in the invention and the present exemplification is to be taken as illustrative and not limitative thereof.

Having described my invention what I 15 desire to secure by Letters Patent and claim is:

1. The combination in a razor blade holder of a pair of holder members pivotally supported therein and adapted to clamp a razor blade between them, a pair of flexible elements integral with each holder member and a guard arm integral with each pair of flexible elements, said guard arms disposed on the opposite sides of said blade and normally in the same plane therewith, either one of said pair of said elements adapted to flex to move its guard arm out of the plane of the razor blade when the latter is being stropped or sharpened.

2. The combination in a razor blade holder of a handle having spaced side plates, a pair of holder members with one end of each pivoted to and between said side plates, detachable locking means integral with said holder members adapted to lock them to each other with a double edge razor blade detachably locked between them, a pair of flexible branch guard arms extending from each holder member and a main guard arm integral with each pair of branch guard arms, said main guard arms disposed on the opposite sides of said razor blade adjacent to the cutting edges thereof and normally in the same plane with said blade, said guard arms constituting protectors for the opposite edges of the razor blade, either pair of said branch guard arms adapted to flex to move its main guard arm out of the plane of said blade when the latter is being stropped or sharpened, said holder members with said razor blade adapted to swing to oppa-

site positions on the handle and adapted to be detachably locked thereto in proper position, to alternately sharpen the opposite cutting edges of the razor blade.

3. The combination in a razor blade holder of a handle having spaced side plates, a pair of holder members with one end of each pivoted to and between said side plates, detachable locking means for said holder members adapted to lock them to each other with a double edge razor blade detachably locked between them, a curved depression at the outer end of each holder member, said depressions normally bearing against each other, a pair of flexible branch guard arms of a width greater than their thickness, extending from each holder member and a main guard arm of a width greater than its thickness integral with each pair of branch guard arms, the said main guard arms disposed on the opposite sides of said razor blade adjacent to the cutting edges thereof and substantially in the same plane with said blade, either pair of said branch guard arms adapted to flex to move its main guard arm out of the plane of said blade, when the latter is being stropped or sharpened, said holder members with said razor blade adapted to swing to opposite positions on the handle to be detachably locked into proper position, to alternately sharpen the opposite cutting edges of the razor blade.

4. The combination in a razor blade holder of a handle, a pair of side plates associated with the handle, a guard and support for a double edge razor blade, said guard and support adapted to be clamped by said side plates, said guard having two pairs of flexible branch guard arms each with a thickness less than its width and a main guard arm of a thickness less than its width, each main guard arm integral with its branch guard arms, said guard adapted to be clamped between said side plates with a razor blade held in position to be stropped or sharpened.

Signed at the borough of Manhattan, city of New York in the county of New York and State of New York this 29 day of July, A. D. 1924.

JOHN HOLTZMAN.
